UNITED STATES PATENT OFFICE.

CHARLES L. MAYHEW, OF NEWARK, NEW JERSEY.

DESIGN FOR A CYLINDER-HEAD FOR TRIPLE-CYLINDER ENGINES.

SPECIFICATION forming part of Design No. 31,412, dated August 15, 1899.

Application filed July 21, 1899. Serial No. 724,664. Term of patent 14 years.

To all whom it may concern:

Be it known that I, CHARLES L. MAYHEW, a citizen of the United States, and a resident of Newark, in the county of Essex and State 5 of New Jersey, have invented a certain new and useful Design for a Cylinder-Head for Triple-Cylinder Engines, of which the following is a specification, reference being had to the accompanying drawings, forming part of 10 the same, in which—

Figure 1 is an obverse face view in perspective of a cylinder-head embodying my new design, and Fig. 2 is a reverse face view in perspective of the same.

The cylinder-head consists of a block of 15 material (I use metal) which is substantially flat or plane-faced on both its respective opposite sides and which comprises a central portion or body A, one edge of which is partially bounded by a single curve at a and the opposite edge of which describes two similar irregular curves at a' a'' , two substantially 20 similar irregularly-circular ends B B', respectively located on opposite sides of said central portion or body and each of somewhat lesser area than that of said central portion or body, and a semicircular longitudinally circularly apertured projection C, extending 25 transversely of the single-curve edge a of said central portion or body and between said portion or body and one of said circular ends thereon, the block being circularly recessed 30 on its reverse plane face at a^3 in the central portion or body adjacent to the single-curve edge a thereof and at b and b' in the respective circular ends B and B' thereof, as shown 35 in Fig. 2, and having that portion of its obverse face at a^4 which is coincident with the recessed part of the central portion or body 40 A in a plane below the plane of the remaining part of said obverse face, with circular recesses a^5 a^6 in its said obverse face adjacent to the double-curve edge of the central portion or body and respectively coincident to the described curves a' and a'' thereof, and 45 apertures a^7 a^8 respectively extending transversely through the block from the bottoms of said recesses a^5 a^6 , as shown in Fig. 1.

A convex surface c extends from the 50 pressed plane face a^4 of the recessed part of the central portion or body A, on its obverse

side, to the obverse end of the projection C. Semicircular longitudinally-apertured lugs a^9 extend transversely of the edges of the block at several points thereon. Longitudinally-apertured lugs b^2 b^3 respectively project in the same axial line radially from the circular ends at opposite extremes of the block, and irregularly oval lugs b^4 b^5 respectively project radially from said circular ends B B' adjacently to the said lugs b^2 b^3 thereon.

The essential features of the described design for a cylinder-head are a central portion or body, one edge of which is partially bounded by a single curve and the opposite edge of which describes two similar irregular curves, two substantially similar irregularly-circular ends, each of somewhat less area than the central portion or body and respectively on opposite sides thereof, and a semicircular longitudinally-apertured projection extending transversely of the single-curve edge of said central portion or body between said portion or body and one of said circular ends, with circular recesses in the reverse plane face of said central portion or body adjacent to its single-curve edge and in said face of the circular ends and with the part of the obverse face of said central portion or body which is coincident with the described recess therein below the plane of the remainder of said face of said portion or body and that of said circular ends, circular recesses in said obverse face of said central portion or body adjacent to the double-curve edge thereof and respectively coincident to said curves on said edge, and apertures transverse of said central portion or body respectively extending from the bottoms of said last-named recesses therein, all substantially as shown and described.

What I claim as my invention, and desire to secure by Letters Patent, is—

The design for a cylinder-head for triple-cylinder engine herein shown and described.

Signed at New York, in the county of New York and State of New York, this 14th day of July, A. D. 1899.

CHARLES L. MAYHEW.
